US00D929318S

(12) **United States Design Patent** (10) **Patent No.:** **US D929,318 S**
Browning et al. (45) **Date of Patent:** **** Aug. 31, 2021**

(54) **BATTERY FOR AN ELECTRONIC DEVICE**(71) Applicant: **Apple Inc.**, Cupertino, CA (US)(72) Inventors: **Lucy E. Browning**, San Francisco, CA (US); **Sawyer Isaac Cohen**, Menlo Park, CA (US); **Richard Hung Minh Dinh**, Saratoga, CA (US); **Devon A. Monaco**, San Jose, CA (US)(73) Assignee: **Apple Inc.**, Cupertino, CA (US)(**) Term: **15 Years**(21) Appl. No.: **29/714,462**(22) Filed: **Nov. 22, 2019**(51) LOC (13) Cl. **13-02**

(52) U.S. Cl.

USPC ..... **D13/103**(58) **Field of Classification Search**USPC D13/102-106, 110, 118-119, 184

(57) **CLAIM**

The ornamental design for a battery for an electronic device, as shown.

DESCRIPTION

FIG. 1 is a bottom front perspective view of a battery for an electronic device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
